UNITED STATES PATENT OFFICE.

WILLIAM G. PARMELE, OF SEATTLE, WASHINGTON.

ROTARY STEAM ENGINE.

Application filed November 7, 1925. Serial No. 67,622.

This invention relates to steam engines and more particularly steam engines of the rotary type, the primary object of the invention being to provide a novel form of steam engine wherein a fluid-tight connection will be maintained between the sliding abutment and blade of the piston at all times.

An important object of the invention is to provide means whereby the sliding abutment will be automatically moved to the limit of its upward movement by the action of the blade of the piston.

Another important object of the invention is to provide a novel form of piston to insure against leakage of steam between the side faces of the piston and engine wall.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a longitudinal sectional view through an engine constructed in accordance with the invention.

Figure 2 is a sectional view taken on line 2-2 of Figure 1.

Figure 3 is a fragmental end elevational view of the engine.

Figure 4 is a fragmental sectional view through the upper portion of the engine.

Figure 5 is a perspective view of the expansive washer.

Figure 6 is a perspective view of the expansive washer clamping member.

Referring to the drawings in detail, the reference character 5 indicates the cylinder of the engine, which is formed preferably in two parts which are bolted together by means of bolts 6, the lower section of the cylinder being provided with a base 7 as shown by Figure 1.

The reference character 8 indicates the steam chest which is bolted to the upper section of the cylinder, at 9, the steam chest 8 being provided with a main opening 10 and lateral passageways 11 and 12 respectively, communicating with the opening 10, the passageways communicating with the interior of the cylinder through the passageways 13.

Valve members 14, which are of the rotary type control the passage of steam through the passageways 11 and 12 and 13, in a manner to be hereinafter more fully described. The controlling valve for controlling the passage of steam from the main steam supply is shown at 15 and controls the passage of steam to the main opening 10.

Adjacent to the steam chest are exhaust valves 16 and 17 respectively which are connected with the valves 14 through the gears 18, 19 and 20, there being provided a lever 21 connected with one of the gears 18 so that as the lever 21 is rotated, the valve members will be moved simultaneously to reverse the operation of the engine.

Operating within the cylinder is the piston 22 mounted on the shaft 23 that operates in suitable bearings carried by the cylinder. Forming a part of the piston is a blade 24 that extends to a position engaging the inner surface of the cylinder as shown by Figure 1. Expansive washers 25 are positioned on opposite sides of the blade 24 and have their upper and lower edges formed at right angles, the upper edges thereof sweeping the inner surface of the cylinder.

Securing members shown more clearly by Figure 6 of the drawings, include elongated metallic members 26 which are formed with openings 27 through which the securing screws 28 pass to secure the washers to the blades 24, flanges 29 being provided on the members 26 to engage the right angled extremities of the washers to hold them in position.

Each of these members 26 includes a central flange portion 30 that has its upper and lower edges cut away as at 31 to receive portions of the washers. These central flange portions have inclined edges 32 that move under the sliding abutment 33 to move the sliding abutment into and out of engagement with the rotor.

At the lower end of the sliding abutment 33 are washers 34 that are adapted to engage the piston 22 and provide a fluid-tight connection therebetween.

The piston embodies an inner or main section 35 and disk-like end sections 36, the sections 35 and 36 being provided with cut out portions 37 to accommodate coiled springs 38 that normally exert a lateral pressure on the disk-like end sections 36 forcing

them into close engagement with the inner surfaces of the cylinder.

In the operation of the device, steam is admitted to the cylinder between the sliding abutment 33 and the blade of the piston, the valves being set in a position as shown by Figure 1, whereupon the piston is rotated in the direction of the arrow as shown by Figure 1, until the piston has made a complete revolution which piston in making the revolution contacts with the sliding abutment to move the same upwardly within the opening 10, cutting off the supply of steam to the passageway 11 and insuring against a back pressure as the blade moves under the sliding abutment 33.

With the valves set in this position, it will be obvious that the spent steam will exhaust through the valve 17.

It might be further stated that rings 39 span the space between the central section and disk-like end sections of the piston to

prevent the steam from entering between the sections 35 and 36.

I claim:—

In a rotary steam engine, a cylinder, a piston mounted for rotation within the cylinder and having a blade adapted to sweep the inner surface of the cylinder, rectangular flanged expansible washers fitted over the blade and being of lengths and widths equal to the length and width of the blade, metallic members having flanges, secured within the expansible washers to insure a fluid-tight connection between the blade and cylinder, a central flange member forming a part of each metallic member and adapted to rest on the piston to hold the metallic members in upright positions, and means co-operating with the blade for controlling the passage of fluid to and from the cylinder.

In testimony that I claim the foregoing as my own, I have hereto affixed my signature.

WILLIAM G. PARMELE.
